UNITED STATES PATENT OFFICE.

GEORGE W. BLAIR, OF PITTSBURG, PENNSYLVANIA.

DESIGN FOR A LAMP-CHIMNEY.

SPECIFICATION forming part of Design No. 26,350, dated December 1, 1896.

Application filed October 28, 1896. Serial No. 610,375. Term of patent 14 years.

To all whom it may concern:

Be it known that I, GEORGE W. BLAIR, of Pittsburg, in the county of Allegheny and State of Pennsylvania, have invented a new and original Design for Lamp Chimneys and Globes, of which the following is a full, clear, and exact description, reference being had to the accompanying drawings, forming part of this specification, in which—

10. Figure 1 shows in side elevation a lamp-chimney embodying my design, and Fig. 2 is a vertical section showing the figured part thereof.

The design consists in a lamp chimney or globe having on its exterior and interior surfaces a pattern substantially as hereinafter described, and shown in the drawings.

In the drawings, 2 represents a lamp-chimney, the lower part of which, opposite to the

position of the light, is formed with a surface pattern comprising a series of circumferential parallel grooves, and on the interior of the glass a corresponding pattern, but in reverse, the grooves on the outside of the glass registering with the ridges on the interior, and vice versa.

The design on the upper part of the chimney is not of the essence of my invention.

I claim—

The design for lamp chimneys or globes substantially as herein shown and described.

In testimony whereof I have hereunto set my hand.

GEORGE W. BLAIR.
